RAZOR

Edward Siegel, New York, N. Y.

Application August 2, 1935, Serial No. 34,333

4 Claims. (Cl. 30—48)

This invention relates to an improvement in razors, and more particularly of the character shown and described in my co-pending applications for patent, Serial No. 707,881 filed January 23, 1934, and Serial No. 638,313 filed October 18, 1932. In said application for patent, Serial No. 707,881, a novel form of razor blade and holder therefor are shown, in which the blade is of the wafer type and has parallel cutting edges; a slot 10 running lengthwise of the blade at an oblique angle to the edges, and the holder acts to flex the blade about an axis of curvature extending along the blade at an oblique angle to the cutting edges. With said structure, the blade is so flexed 15 that one of its cutting edges ascends and the other cutting edge descends at the same end of the razor, and by this particular inclination of the cutting edges a desirable shearing cutting effect is obtained.

20 The object of this invention is to provide a blade holder for a blade of the character just described which will clamp and flex the blade in the manner heretofore set forth and in such a way that the cutting edges of the blade will tend to lie 25 perfectly straight and in absolute parallelism with the edges of the holder.

In the accompanying drawing, Fig. 1 is a front elevation of a razor constructed in accordance with this invention; Fig. 2 is a plan view of the 30 same; Fig. 3 is a plan view of the blade table or guard; Fig. 4 is a view of the underside of the cap; Fig. 5 is a sectional view through the razor on the line 5—5 of Fig. 1, looking in the direction of the arrows; Fig. 6 is an end view of the razor; 35 and Fig. 7 is a plan view of the blade.

The razor shown in the drawing is of the so-called "hoe" type safety razor and includes a handle 61, and a holder for a double-edged wafer type blade, comprising a blade table or guard 62 and a blade cap 63. A double-edged blade 64 shown in Fig. 7, is adapted to be clamped between the two members of the holder in such a position that the cutting edges 65 of the blade are brought over the marginal combs 66 of the blade table 62, 40 so that the latter member serves as a safety or guard plate. The blade 64, substantially of rhomboidal outline, is provided with a centrally located elongated slot 67, enlarged at its ends as shown at 68 and also provided with a central enlarged portion 69, these enlarged portions being 45 arranged to fit over the three studs 70 projecting downwardly from the underside of the cap 63, these studs passing through the enlarged parts 68 and 69 of slot 67 in the blade and then projecting through complementary openings pro-

vided in the blade table 62. The cap 63 is formed with ribs 71 located between and connecting the several studs 70, these ribs fitting into those portions of the slot 67 which lie between the enlarged parts 68 and 69 thereof and into a complementary groove provided in the table 62. The central lug 70 on cap 63 is threaded in the usual way for reception into the upper end of the handle 61. The general structure of the blade shown at 64 is described and claimed in my co-pending application, Serial No. 707,881, and is not claimed per se herein.

The under surface of the blade cap 63, instead of being wholly curved or formed with a continuous curved face, has a centrally curved surface 15 72 and two substantially flat, inclined surfaces 73 lying on either side of the central curved portion and extending from the edges of the curved surface to the parallel longitudinal edges of the cap. These two flat surfaces 73 may be substantially triangular in outline, this being dependent upon the width of the central curved portion. If the curved portion is made relatively narrow, the flat portions may be trapezoidal, as clearly shown in Fig. 4.

The upper surface of the blade cap may 20 conform to the lower surface, that is to say, it may have a centrally curved portion and two flat edge surfaces or it may be rounded off into a continuous smooth curve.

It will be noted that the central curved portion 72 on cap 63 lies at an oblique angle to the parallel edges of the cap 63 and extends thereby co-extensively with the central slot 67 in the blade and with the axis of curvature of the blade when the 35 blade is flexed in the holder. The upper surface of the blade table 62 conforms substantially to the under surface of the cap, that is to say, it has a central curved portion 74 similar to the curved surface 72 on the under face of cap 63, 40 but of a slightly flatter curve, as clearly seen in Figs. 5 and 6, to avoid the imposition of a sharp bend on the blade, and the two flat surfaces corresponding to those shown at 73 on the under face of the cap 63. The shape and position of the blade 45 when clamped in cutting position is determined primarily by the cap and it is therefore not essential that the upper surface of the table be of exactly the same form as the under surface of the cap.

When the blade is placed in the holder between the table and cap, the blade will be flexed about a line B—B (Fig. 7) comprising the median line of the slot 67, which is at an angle to the cutting edges and thus when the blade is clamped in 55

position in the holder, the cutting edges will be inclined both with respect to a plane perpendicular to the handle and to a plane defined by the center line of the handle and the line B—B. 5 Since the flat, inclined surfaces 73 located adjacent to the parallel longitudinal edges of the cap 63 are plane surfaces, the portions of the blade adjacent to the cutting edges will necessarily lie against the same and these flat surfaces 10 will hold the cutting edges in a straight line so that the distance between the edge of the blade and the comb portions 66 on the guard will be maintained constantly uniform for the entire length of the blade to ensure a wholly satisfactory 15 shave.

While the structure herein described and claimed is shown as applied to a razor of the character disclosed in my co-pending application, Serial No. 707,881, wherein the blade is provided with parallel cutting edges, it will be obvious that the structure of the cap and table of the holder may be readily used in conjunction with a blade of truncated triangular outline having non-parallel edges of the character shown in 25 my co-pending application, Serial No. 638,313 and with other types of blades capable of fitting and being satisfactorily used in a holder of the character described and claimed herein.

What I claim is:

- 30 1. In a razor of the character described, a blade table and a cap between which a wafer-type blade is clamped, the blade being received and flexed therebetween about an axis of curvature extending along the blade at an oblique angle to its cutting edges, the cap having an under face 35 formed with a curved surface extending co-extensively with the axis of curvature of the blade and having the longitudinal edges of said curved surface extending substantially parallel to the axis of curvature of the blade, said cap having flat surfaces of substantially trapezoidal outline 40 on its under face extending from the termination of the curved surface thereon to the longitudinal edges of the cap, the table having co-operating flat surfaces on its upper face, the flat surfaces on the cap and table co-operating in forming straight cutting edges on the blade and plane surfaces on the blade in back of said cutting edges when the blade is clamped and flexed 45 between the cap and table.
-2. In a razor of the character described, a blade table and cap between which a wafer-type blade is clamped and flexed, the blade being flexed about an axis of curvature extending along the

blade at an oblique angle to its cutting edges, the under face of the cap being provided with an elongated curved area extending at an oblique angle to the longitudinal edges of the cap, said cap having flat, substantially trapezoidal surfaces 5 on its under face extending inwardly from its longitudinal edges toward the curved surface, whereby a blade clamped between the cap and table will conform in shape to the flat and curved surfaces on the under face of the cap and the cutting edges of said blade will be straight and portions of said blade in back of said cutting edges will be flat.

3. In a razor of the character described, a top, a blade table having guard portions, a blade 15 clamped and flexed between said top and table, said blade having parallel cutting edges and a central slot lying at an oblique angle to the cutting edges, said top and table flexing the blade between them so that the axis of curvature of the blade extends co-extensively with the slot therein, a curved under face on the top extending along and lying co-extensively with the slot in the blade and having its longitudinal edges extending parallel to the axis of curvature of the 20 blade, and flat triangulated inclined surfaces on the under face of the top overlying parts of the blade adjacent to the cutting edges thereon and causing said edges and portions of the blade rearwardly thereof to lie straight along the guard 25 portions on the table.

4. In a razor of the character described, a blade table and a cap between which a wafer-type blade is clamped, the blade being received and flexed therebetween about an axis of curvature extending along the blade at an oblique angle to the cutting edges thereon, the cap having an under face formed with a curved surface extending co-extensively with the axis of curvature of the blade, the cap having flat trapezoidal surfaces 35 on its under face extending from the side limits of curved surface thereon to the longitudinal edges of the cap, the table having co-operating, inclined flat surfaces on its upper face, co-operating 40 in the formation of straight cutting edges and flat surfaces rearwardly of said edges on the blade when the blade is flexed between the cap and table, the table also having a curved surface on its upper face situated between its flat surfaces, said curved surface being of flatter 45 curvature than the curved surface on the under face of the cap.

EDWARD SIEGEL.
